UNITED STATES PATENT OFFICE.

WILLIAM A. SPIER, OF ATTLEBORO, MASSACHUSETTS.

DESIGN FOR A PIN OR SIMILAR ARTICLE.

SPECIFICATION forming part of Design No. 34,393, dated April 23, 1901.

Application filed March 25, 1901. Serial No. 52,869. Term of patent 3½ years.

To all whom it may concern:

Be it known that I, WILLIAM A. SPIER, a citizen of the United States, residing at Attleboro, in the county of Bristol and State of Massachusetts, have invented and produced a new and original Design for a Pin or Similar Article, of which the following is a specification, reference being had therein to the accompanying drawings.

10 Figure 1 is a plan view of a pin, showing my new design; and Fig. 2 is a central vertical section of the same.

As shown in the drawings, the leading or material features of my design are as follows:

15 The contour of the pin-body represents a human being *c*, holding in one hand *o* by its handle *a* the representation of a culinary

utensil, whose outline is completed by the circular body portion *b*. Attached to the body-back is a pin *d*.

20 It is evident that this design is applicable to all classes of pins and other similar articles.

Having described my invention, what I claim as new, and desire to secure by Letters 25 Patent, is—

The design for a pin or similar article as herein shown and described.

In testimony whereof I have affixed my signature in presence of two witnesses.

WILLIAM A. SPIER.

Witnesses:

SAMUEL M. ERNSTEIN,
ARTHUR H. ARMSTRONG.
